(57) CLAIM

The ornamental design for an electronic device, as shown and described.

DESCRIPTION

FIG. 1 is a front perspective view of a first embodiment of an electronic device showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is a front perspective view of a second embodiment of an electronic device showing my new design;

FIG. 10 is a front view thereof;

FIG. 11 is a rear view thereof;

FIG. 12 is a left-side view thereof;

FIG. 13 is a right-side view thereof;

FIG. 14 is a top view thereof;

FIG. 15 is a bottom view thereof;

FIG. 16 is a rear perspective view thereof;

FIG. 17 is a front perspective view of a third embodiment of an electronic device showing my new design;

FIG. 18 is a front view thereof;

FIG. 19 is a rear view thereof;

FIG. 20 is a left-side view thereof;

FIG. 21 is a right-side view thereof;

FIG. 22 is a top view thereof;

FIG. 23 is a bottom view thereof;

FIG. 24 is a rear perspective view thereof;

FIG. 25 is a front perspective view of a fourth embodiment of an electronic device showing my new design;

FIG. 26 is a front view thereof;

FIG. 27 is a rear view thereof;

FIG. 28 is a left-side view thereof;

FIG. 29 is a right-side view thereof;

FIG. 30 is a top view thereof;

FIG. 31 is a bottom view thereof;

FIG. 32 is a rear perspective view thereof;

FIG. 33 is a front perspective view of a fifth embodiment of an electronic device showing my new design;

FIG. 34 is a front view thereof;

FIG. 35 is a rear view thereof;

FIG. 36 is a left-side view thereof;

FIG. 37 is a right-side view thereof;

FIG. 38 is a top view thereof;

FIG. 39 is a bottom view thereof;

FIG. 40 is a rear perspective view thereof;

FIG. 41 is a front perspective view of a sixth embodiment of an electronic device showing my new design;

FIG. 42 is a front view thereof;

FIG. 43 is a rear view thereof;

FIG. 44 is a left-side view thereof;

FIG. 45 is a right-side view thereof;

FIG. 46 is a top view thereof;

FIG. 47 is a bottom view thereof; and,

FIG. 48 is a rear perspective view thereof.

The evenly-dashed broken lines in the drawings illustrate portions of the electronic device that form no part of the claimed design.
